UNITED STATES PATENT OFFICE.

YVES MARIE CRÉCHRIOU, OF NEW MONTEREY, CALIFORNIA.

POOL AND BILLIARD TABLE STRETCHER.

1,003,880.

Specification of Letters Patent. Patented Sept. 19, 1911.

Application filed June 1, 1910, Serial No. 564,428. Renewed March 30, 1911. Serial No. 618,006.

To all whom it may concern:

Be it known that I, YVES MARIE CRÉCHRIOU, a citizen of the United States, residing at New Monterey, in the county of 5 Monterey and State of California, have invented new and useful Improvements in Pool and Billiard Table Stretchers, of which the following is a specification.

This invention relates to stretchers for 10 billiard and pool tables, the object of the invention being to do away with the old method of tacking the cloth on tables of the class referred to and substitute therefor simple and novel mechanism whereby the 15 cloth may be evenly stretched over the surface of the table and taken up as occasion may demand, the mechanism also facilitating the turning or reversing of the cloth when necessary.

20 The usual way of stretching cloth on pool and billiard tables consists in tacking the margin of the cloth all around the table and when the cloth becomes loose it is necessary to remove the rails of the table, re- 25 move all of the tacks and drive the same again after taking up the slack which greatly mutilates and injures the cloth and also the frame of the table which becomes literally honey-combed with tack holes. By 30 means of the invention hereinafter fully described, these serious objections are entirely overcome and much time and labor is saved.

With the above and other objects in view, 35 the invention consists in the novel construction, combination and arrangement of parts hereinafter fully described, illustrated and claimed.

In the accompanying drawings:—Figure 40 1 is a plan view of a billiard table showing the improvement applied thereto. Fig. 2 is a side elevation of the same. Fig. 3 is an enlarged cross section through one of the tension rollers. Fig. 4 is a detail perspective 45 view of the clamping bar and binding strip detached. Fig. 5 shows the improvement applied to a pool table which is shown in plan. Fig. 6 is a view in elevation of one of the roller brackets. Fig. 7 is a side elevation of said bracket. Fig. 8 is a front elevation of the bracket, showing also the pawl and ratchet mechanism for holding the roller. Fig. 9 is a side elevation of the 50 same. Fig. 10 is a sectional elevation of the device showing the cloth engaged and held by the roller. Fig. 11 is a detail view

showing one of the pockets and the clamping wire associated therewith.

In carrying out the present invention, I provide in connection with a billiard table 60 as shown in Fig. 1, or a pool table as shown in Fig. 5, a series of tension rollers 1 each of which is in the form of a hollow cylindrical shell provided at one side with a slot 2 extending nearly the entire length of the 65 roller and adapted to receive a clamping bar 3 which is preferably of wood, said clamping bar being of the same length as the slot 2 and of a width slightly in excess of the diameter of the roller so as to pass 70 diametrically through the roller as illustrated in Figs. 3 and 10.

The clamping bar 3 is removably fastened in place in the roller by means of a plurality of screws 4 or their equivalent 75 which pass transversely through the clamping bar 3 and have their threaded ends fitted in threaded openings in the roller as shown at 5. To the opposite or outer edge of the clamping bar 3 there is fastened a binding strip 6 which is held tightly against the clamping bar 3 by means of the screws 4 which fasten the clamping bar to the roller. The edge of the cloth shown at 7 is inserted through the slot into the roller 1 and is held between the edge of the roller adjacent to the slot 2 and side face of the clamping bar 3 and is held still more securely by the binding strip 6, which at one side of the clamping bar 3 overlaps and 80 overhangs the peripheral surface of the holder so as to securely confine or clamp the cloth against the roller, all as clearly shown in Fig. 3.

Under the preferred application of the 85 invention, two of such rollers 1 are mounted at each side of the table and one of such rollers at each end of the table, and each roller is mounted in a pair of brackets 8, one at or near each end of each roller. Each 90 bracket is of sectional construction as best illustrated in Fig. 7 comprising a base 9 adapted to fasten to the side of the table by screws 9' or their equivalent. The projecting portion 10 of the bracket is recessed 100 as shown at 11 to receive the end of the roller and is also provided with a pivoted section 12 which is pivotally connected at 13 to the base 9 and constructed at its free end to overlap the fixed portion of the bracket, 105 as shown at 14, the said overlapping portions of the bracket being secured together 110

by a suitable fastening device which may consist of a screw. The brackets thus formed enable the rollers 1 to be easily connected to or disconnected from the table.

- 5 Each roller is further provided at one or both ends with a ratchet wheel 16 fast thereon and engaged by a pawl or detent 17 which is pivoted at 18 to the base of the bracket, said pawl serving to prevent the 10 roller from turning backward after the same has been turned in a direction to stretch the cloth over the surface of the table.

Where the ends of the rails adjoin, the 15 cloth is cut from the edge inward as shown at 19 and 20 so as not to interfere with the stretching operation, and in case of a pool table portions of the cloth are removed at the points 21 and 22 to make allowance for 20 the usual pockets 23 around which the cloth may be secured by a clamping wire 24 after having been stretched by the mechanism above fully described.

It will be understood that elongated slits 25 will be cut in the marginal portions of the cloth to make allowance for the bolts which secure the side and end rails in place and to allow for the necessary stretching of the cloth past said bolts. When the cloth becomes 30 loose, the bolts at one side and both ends of the table are loosened and the rollers turned to take up the slack, after which the bolts are replaced. To turn or reverse the cloth, all of the side and end rails are removed 35 from the table, the rollers are loosened or freed from the ratchets and the clamping bars 4 are taken out of the rollers. After turning the cloth, the edges thereof are again inserted in the proper rollers and the 40 clamping bars 3 replaced. The rollers are then turned in the proper direction until the cloth is sufficiently stretched, whereupon the rollers are automatically held by the ratchets. The side and end rails are then 45 replaced on the table.

Having thus described the invention, what I claim as new, is:—

1. In a cloth stretcher for billiard and pool tables, the combination, with a table, of 50 stretcher rolls arranged at the opposite sides of the table, similar stretcher rolls arranged at the opposite ends of the table, said rolls being provided with means to grip the cloth, and means for locking each roll in adjusted 55 position to stretch cloth to the desired tension.

2. In a cloth stretcher for billiard and

pool tables, the combination with a table, of a pair of rolls arranged longitudinally at each side of the table on the opposite sides 60 of the transverse central portion thereof, similar rolls arranged at the ends of the table, said rolls being provided with gripping devices, and means for locking the rolls in adjusted position to hold the cloth at a 65 desired tension.

3. In a cloth stretcher for billiard and pool tables, the combination, with a table, of stretcher rolls journaled at the sides and ends of the table, each of said rolls comprising 70 a hollow body provided at one side with a longitudinal slot, a stretcher bar mounted in said hollow body and projecting through the slot to clamp the edge of the cloth between the same and one of the end walls of 75 the slot, and means for locking each roll against retrograde rotation.

4. In a cloth stretcher for billiard and pool tables, the combination, with a table, of 80 stretcher rolls journaled at the sides and ends of the table, each roll comprising a hollow body having a longitudinal slot at one side thereof, a clamping bar arranged with the hollow body and projecting through said slot to clamp the edge of the cloth between 85 the same and one of the walls of the slot, a clamping strip longitudinally secured to the projecting edge of the bar to overhang and clamp the cloth against the periphery of the roll, and means for securing each roll against 90 retrograde rotation.

5. In a cloth stretcher for billiard and pool tables, the combination, with a table, of 95 stretcher rolls journaled at the ends of the table, pairs of similar rolls journaled at the sides of the table in longitudinal alignment and at the opposite sides of the transverse central portion thereof, each of said stretcher rolls comprising a hollow body having a longitudinal slot in one side thereof, a clamping 100 bar arranged in said hollow body and projecting through said slot to clamp the edge of the cloth against one of the walls thereof, a clamping strip carried by the bar to engage and press the cloth against the periphery of 105 the roll, and a locking means for holding the rolls against retrograde rotation.

In testimony whereof I affix my signature in presence of two witnesses.

YVES MARIE CRÉCHRIOU.
